THE NORRIS PETERS CO., PHOTO-LITHO., WASHINGTON, D. C.

UNITED STATES PATENT OFFICE.

FRED M. WALKER, OF DETROIT, MICHIGAN.

DESIGN FOR A LIGHT-GLOBE.

53,389.

Specification for Design. Patented May 27, 1919.

Application filed August 30, 1918. Serial No. 252,130. Term of patent 7 years.

To all whom it may concern:

Be it known that I, FRED M. WALKER, a citizen of the United States, residing at Detroit, Wayne county, Michigan, have invented a new, original, and ornamental Design for a Light-Globe, of which the following is a specification, reference being had to the accompanying drawing, forming part thereof.

The figure is an elevational view of a light globe, showing my new design.

I claim:

The ornamental design for a light globe, as shown.

FRED M. WALKER.

Witnesses:

F. S. WALKER,
ALVA M. JOHNSON.
